(57) **CLAIM**

The ornamental design for an electric grinder, as shown and described.

DESCRIPTION

FIG. 1 is a top, front, left perspective view of a first embodiment of an electric grinder showing my new design; FIG. 2 is a bottom, rear, right perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a bottom, rear, right perspective view of a second embodiment of the electric grinder where the inner rear column of the electric grinder is removed; and, FIG. 10 is a rear elevational view thereof. The broken lines in the drawings depict portions of the electric grinder that form no part of the claimed design.

1 Claim, 10 Drawing Sheets
